UNITED STATES PATENT OFFICE.

HENRY C. CURRIER, OF RUMFORD, MAINE.

SNUBBING-MACHINE.

1,273,745.

Specification of Letters Patent. Patented July 23, 1918.

Application filed February 9, 1918. Serial No. 216,194.

To all whom it may concern:

Be it known that I, HENRY C. CURRIER, a citizen of the United States of America, and resident of Rumford, in the county of 5 Oxford and State of Maine, have invented certain new and useful Improvements in Snubbing-Machines, of which the following is a specification.

This invention relates to friction applying 10 means used in lumbering or other places where it is necessary to ease heavy loads down steep inclines.

An object of this invention is to provide 15 novel means for lowering the load, while at the same time, returning a previously lowered supporting means, so that it may be used for another load while one of the loaded carrying means is descending, thus 20 making it automatic in operation while at the same time affording means for creating friction to prevent the load from traveling at a damaging speed or getting beyond control in its descent.

A further object of this invention is to 25 provide friction creating members over which a flexible device is wound and novel means for clamping the flexible member or increasing the frictional contact thereof so that it will operate as a brake for safeguarding the action of the device, and a still 30 further object of the invention is to provide drums with pulleys connected by a flexible member associated with means for retarding the travel of the flexible member 35 and therefore retarding the motion of the drums over which the flexible member operates.

With the foregoing and other objects in view, the invention consists in the details 40 of construction, and in the arrangement and combination of parts to be hereinafter more fully set forth and claimed.

In describing the invention in detail, reference will be had to the accompanying 45 drawings forming part of this specification, wherein like characters denote corresponding parts in the several views, and in which—

Figure 1 illustrates a plan view of my 50 invention;

Fig. 2 illustrates a side elevation;

Fig. 3 illustrates a rear end view thereof; and

Fig. 4 illustrates a detail view of one of 55 the friction increasing devices.

In these drawings 10 denotes a frame having pairs of journal bearings 11, 12, 13, 14 and 15 employed for rotatably supporting shafts, as will presently appear.

The size of the device may be changed to 60 suit particular requirements and I, therefore, do not wish to be limited with respect to the proportions.

Near the rear end of the frame, there is 65 an inclined sill 16 having pintles or shafts 17 and 18 for the grooved pulleys 19 and 20 respectively. The shafts 17 and 18 are

inclined so that the pulleys which rotate in them are tilted or otherwise obliquely disposed so that the flexible member 21 which 70 runs over them travels obliquely at the rear of the frame. A double drum 22 has a shaft 23 in the bearing 11 and the flexible member 21 is overwound on one end of the drum and underwound on the other end of the 75 drum and said underwound portion is first engaged by the pulley 19, then running up to the pulley 20 and overwinding on the drum at the end opposite the underwound portion. Another drum 24 is mounted on 80 a shaft 25 in the bearings 12 and the flexible member is wound on the drum, a number of convolutions being applied to the drum so as to increase the friction of the drums as the flexible member is moved. A shaft 26 85 is journaled in the bearings 13 and it has double grooved pulleys 27 and 28 on it around which the flexible member is also wound and the extensions of that part of the flexible member that has been described 90 travel with relation to the frame, one end 29 moving in one direction while the end 30 is traveling in the opposite direction; that is to say if the end 29 has a coupling 95 of any appropriate style, it is attached to a load being lowered, then the end of the portion 30 is traveling toward the friction producing member and vice versa for the purpose indicated.

The rotation of the drums 22 and 24 is 100 checked or retarded by the use of a braking mechanism comprising the pulleys 31 and 32 which are on the shafts 23 and 25 respectively, and these pulleys are connected by a flexible device 33 such as a 1 belt engaged by a bar 34 hinged transversely of the frame and mounted on the bracket 35. The end of the bar remote from the pivot is connected to a treadle 36 by which the bar is pressed into engagement with the

belt or flexible member to retard the rotation of the drums, thus controlling the rapidity of travel of the flexible member, regardless of the load.

- 5 A guide roll 37 is mounted on a stud 38 to engage the flexible member, and rotating members such as 39 and 40 are mounted on studs or shafts 41 and 42 respectively fixed on the frame, and the pulleys 39 and 40 are 10 likewise engaged by the flexible member. In order to further control the movement of the flexible member, said flexible member may be forced into engagement with either of the pulleys 39 or 40 and movement of the 15 flexible member will be thereby retarded. In order to accomplish the foregoing result, I mount a shaft 43 in the frame or a portion of the frame so that the said shaft will oscillate somewhat and I mount 20 a pulley or drum 44 on the said shaft so that the pulley or drum can be forced into engagement with the flexible member and clamp it against either the pulley 39 or 40, and I accomplish the result by means of a 25 lever 45, which lever is connected to the shaft 43 on a pintle 46 rising from the post 47 of the frame, so that as the lever is moved on its pivot or pintle, it will clamp the flexible member against one of the pulleys. 30 It is also the purpose of the inventor to have the pulley or frame of such construction that it will contact either the pulley 39 or the pulley 40 as it is moved by the lever, and to that end, it is slightly tapered or 35 beveled so that when it assumes an inclined position as it must to be forced into engagement with the pulleys, it will have a large area of its surface in contact with the pulley toward which it is moved and the 40 friction will be increased and add to the efficiency of the device.

It is to be understood, of course, that if a log is attached to one of the extensions of the flexible member and it is to be lowered 45 down a steep incline, an operator would actuate the parts of the mechanism to permit the log to slowly descend and the friction applied to the drums would be regulated according to the requirements and as 50 one of the extensions of the flexible member would be returning as the other is descending there would be continuous operation of the load lowering device except during the time that the couplings were being applied 55 to or removed from the load.

It has been found that a device made in accordance with this invention is comparatively inexpensive and has proven efficient and satisfactory in use, as well as strong 60 and durable.

I claim:

1. In a snubbing machine, a frame having an inclined sill near the rear end, inclined pulley supporting members on the 65 sill, pulleys mounted on the inclined mem-

bers at different heights, a drum, a flexible member operating over the pulleys, the section of the flexible member running from the lowermost pulley being underwound on the drum and the section running from the upper pulley being overwound on the said drum, a second drum around which the flexible member is wound, extensions of said flexible member adapted for attachment to loads, a shaft having pulleys around which the extensions are wound, and means for guiding the extensions. 70

2. In a snubbing machine, a frame having an inclined sill near the rear end, inclined pulley supporting members on the sill, pulleys mounted on the inclined members at different heights, a drum, a flexible member operating over the pulleys, the section of the flexible member running from the lowermost pulley being underwound on the 75 drum and the section running from the upper pulley being overwound on the said drum, a second drum around which the flexible member is wound, extensions of said flexible member adapted for attachment to loads, a shaft having pulleys around which the extensions are wound, means for guiding the extensions, pulleys having vertical axes with which the flexible extending members 80 coact, and a member adapted to engage either of said pulleys for braking the pulleys. 85

3. In a snubbing machine, a frame having an inclined sill near the rear end, inclined pulley supporting members on the sill, pulleys mounted on the inclined members at different heights, a drum, a flexible member operating over the pulleys, the section of the flexible member running from the lowermost pulley being underwound on the drum and the section running from the upper 90 pulley being overwound on the said drum, a second drum around which the flexible member is wound, extensions of said flexible member adapted for attachment to loads, a shaft having pulleys around which the extensions are wound, means for guiding the extensions, pulleys having vertical axes with which the flexible extending members coact, and a member adapted to engage either of said pulleys for braking the pulleys. 95

4. In a snubbing machine, a frame having an inclined sill near the rear end, inclined pulley supporting members on the sill, pulleys mounted on the inclined members at different heights, a drum, a flexible member operating over the pulleys, the section of the flexible member running from the lowermost pulley being underwound on the 125 drum and the section running from the upper pulley being overwound on the said drum, a second drum around which the flexible member is wound, a brake for the 130

drums, extensions of said flexible member adapted for attachment to loads, a shaft having double grooved pulleys around which the extensions are wound, and means 5 for guiding the extensions.

5. In a snubbing machine, a frame having an inclined sill near the rear end, inclined pulley supporting members on the sill, pulleys mounted on the inclined members at 10 different heights, a drum, a flexible member operating over the pulleys, the section of the flexible member running from the lower-most pulley being underwound on the drum

and the section running from the upper pulley being overwound on the said drum, a 15 second drum around which the flexible member is wound, extensions of said flexible member adapted for attachment to loads, a shaft having double grooved pulleys around which the extensions are wound, means for 20 guiding the extensions, pulleys having vertical axes with which the flexible extending members coact, a member adapted to engage either of said pulleys for braking the pulleys, and a brake for the drums.

HENRY C. CURRIER.
